DESIGN FOR AN AUTO COMPASS

Burl E. Sherrill, Peru, Ind., assignor to Sherrill Research Corporation, Peru, Ind., a corporation of Indiana

Application June 1, 1946, Serial No. 130,319

Term of patent 3½ years

(Cl. D52—1)

To all whom it may concern:

Be it known that I, Burl E. Sherrill, a citizen of the United States and a resident of Peru, in the county of Miami and State of Indiana, have invented a new, original, and ornamental Design for an Auto Compass, of which the following is a specification, reference being had to the accompanying drawing, forming a part thereof, and in which:

Fig. 1 is a perspective view of an auto compass showing my new design;

Fig. 2 is a rear elevational view of the same;

Fig. 3 is a top plan view of the same;

Fig. 4 is a bottom plan view of the same.

I claim:
The ornamental design for an auto compass, as shown.

BURL E. SHERRILL.
